UNITED STATES PATENT OFFICE.

SIDNEY C. GILBERT, OF JACKSON, OHIO.

KEY-ACTION FOR SAXOPHONES AND THE LIKE.

1,228,016.

Specification of Letters Patent.

Patented May 29, 1917.

Application filed April 13, 1916. Serial No. 90,919.

To all whom it may concern:

Be it known that I, SIDNEY C. GILBERT, a citizen of the United States, residing at Jackson, in the county of Jackson and 5 State of Ohio, have invented certain new and useful Improvements in Key-Actions for Saxophones and the like; and I do declare the following to be a full, clear, and exact description of the invention, such as 10 will enable others skilled in the art to which it appertains to make and use the same.

My invention relates broadly to improvements in musical instruments and more particularly to the note controlling means of 15 saxophones and analogous instruments, the aim of the invention being to provide means whereby opening of the valve to sound E flat will automatically open D, and means for automatically opening E flat when E 20 is opened, the last named means serving to open both E and E flat when F is opened. By this arrangement, the great amount of fingering which has heretofore been necessary will be eliminated.

25 With the foregoing general object in view, the invention resides in certain novel features of construction and in unique combinations of parts to be hereinafter fully described and claimed, the descriptive matter being supplemented by the accompanying drawing which constitutes a part of this 30 application and in which:

Figure 1 is an elevation of a portion of a saxophone or similar instrument showing 35 the improved features of construction; and

Fig. 2 is a transverse section taken on the plane indicated by the line 2—2 of Fig. 1.

In specifically describing the construction shown in the drawings above briefly described, similar characters will be placed 40 on corresponding parts throughout the several views and reference will be herein made to the numerous elements by their respective indices. To this end, a portion S of 45 a saxophone is shown equipped with the usual valves or pads P for controlling the notes E, F, E flat and D, said valves or pads being identified in the drawing by placing thereon characters designating the 50 notes which said valves or pads represent. These valves or pads are provided with operating arms A for opening them when said arms are properly actuated by the musician.

55 A rigid finger 1 is secured to the pad of E, the end of said finger being positioned

on the outward path of the operating arm of F, which arm is preferably provided with an anti-friction roller 2 for contact with said finger 1. A second rigid finger 3 is secured to the pad of D and extends therefrom to a point on the outward path of E flat, and a third finger 4 is secured to the pad of E flat and extends into the outward path of the finger 1 of E, the portion of 60 said finger 4 in the path of the finger 1 being preferably in the form of a roller 5.

By the arrangement of the parts shown and described, D may be opened independently of the others, while opening of E flat 70 will simultaneously open D. Also opening of E will open E flat and D; and when F is opened E, E flat and D are simultaneously opened. By providing the construction shown for sounding the notes discussed 75 in the manner set forth, a considerable amount of fingering which has heretofore been necessary is overcome, thus allowing the instrument to be played with less effort.

From the foregoing, taken in connection 80 with the accompanying drawing, the arrangement, manner of operation and advantages of the improved features of construction will be readily understood, and it will be obvious that no changes need be made in 85 the construction of instruments to which the numerous fingers are applied.

In conclusion, I will state that although I have shown and described certain specific details for the attainment of probably the 90 best results, numerous changes may be made within the scope of the invention as claimed without sacrificing the main advantages thereof.

I claim:

1. The combination with three valves of 95 a saxophone or similar instrument; of means for automatically opening one valve when another is opened, and additional means operated by the first named means 100 for automatically opening the third valve when either of the first named valves is opened.

2. The combination with three sound controlling valves of a saxophone or similar instrument, of a rigid finger secured to one of said valves and positioned in the outward path of another valve, and a second rigid finger secured to the third valve and positioned in the outward path of the first 110 named finger.

3. The combination with three sound con-

trolling valves of a saxophone or similar instrument and the operating arms for said valves; of a rigid finger projecting laterally from one valve and having its free end offset outwardly from the instrument and disposed over the arm of another valve, an anti-friction roller on this arm underlying said finger, a second rigid finger projecting laterally from the third valve and having its free end offset outwardly from the in-

strument, and a second anti-friction roller on said second finger overlying the first named finger.

In testimony whereof I have hereunto set my hand in presence of two subscribing 15 witnesses.

SIDNEY C. GILBERT.

Witnesses:

JOHN ROBBINS,
JAMES M. ROBBINS.
